Fig. 6.

Fig. 5.

Fig. 8.

Fig. 7.

Fig. 9.

FIG. 1 is a perspective view of a linoleum layer's corner scribe showing my new design therefor;

FIG. 2 is a plan view of the corner scribe of FIG. 1;

FIG. 3 is an end elevational view looking toward the open end of its base as seen from the lower end of FIG. 2;

FIG. 4 is a side elevational view looking toward the right-hand side of and as projected from FIG. 2;

FIG. 5 is a side elevational view looking toward the left-hand side of FIG. 3;

FIG. 6 is an end view looking toward the left-hand end of FIG. 5;

FIG. 7 is a bottom plan view as seen from below in FIG. 5;

FIG. 8 is a bottom perspective view of the corner scribe looking upwardly toward the closed end of the base and the side corresponding to that of FIG. 5; and

FIG. 9 is a bottom perspective view of the corner scribe looking downwardly toward the open end of the base and the side corresponding to that of FIG. 4.

I claim:

The ornamental design for a linoleum layer's corner scribe, as shown and described.
